UNITED STATES PATENT OFFICE

169,951

COMBINED HOLDING FURNACE AND AUTO-MATIC POURING UNIT

Mario Tama, Morrisville, Pa., assignor to Ajax Engineering Corporation, a corporation of New Jersey

Application December 20, 1952, Serial No. 22,793

Term of patent 14 years

(Cl. D55—1)

To all whom it may concern:

Be it known that I, Mario Tama, a citizen of the Republic of Ecuador, residing at Morrisville, in the county of Bucks and State of Pennsylvania, have invented a new, original, and ornamental Design for a Combined Holding Furnace and Automatic Pouring Unit, of which the following is a specification, reference being had to the accompanying drawing, forming part thereof; wherein,

Fig. 1 is a perspective view of a combined holding furnace and automatic pouring unit, showing my new design;

Fig. 2 is a plan view thereof; and

Fig. 3 is a side view of the same, seen in direction 3—3 of Fig. 2.

The dominant features of my design reside in the parts shown in solid lines in the drawing.

I claim:

The ornamental design for a combined holding furnace and automatic pouring unit, substantially as shown and described.

MARIO TAMA.
